UNITED STATES PATENT OFFICE

ALBERT W. CHARBONNEAU, OF BOSTON, MASSACHUSETTS, ASSIGNOR TO THE ROBERTS SPECIALTY MANUFACTURING COMPANY, INC., OF BOSTON, MASSACHUSETTS, A CORPORATION OF MASSACHUSETTS

COMPOUND APPLIANCE

Application filed November 17, 1928. Serial No. 320,080.

This invention has for its object to provide a simple, inexpensive and compact compound appliance having instrumentalities adapted for a variety of purposes. More particularly the invention is in the nature of an improvement on the combined bottle opener and temporary closure shown and described in the patent to Roberts No. 1,610,158, December 7, 1926, and consists in utilizing certain of the essential portions of the patented construction for the purpose of attaching and housing an added instrumentality, preferably a corkscrew.

The foregoing and other objects of the invention, together with means whereby the latter may be carried into effect, will best be understood from the following description of a preferred illustrative embodiment thereof shown in the accompanying drawings, in which:

Fig. 1 is a perspective view of the combined appliance, showing the same in use as a temporary bottle closure.

Fig. 2 is a side elevation thereof, showing the corkscrew in its housed position.

Fig. 3 is a similar view showing the corkscrew in the released position which it tends normally to assume with its point disengaged from its housing socket.

Fig. 4 is a section taken substantially on the line 4—4, Fig. 2, of the appliance removed from the bottle, showing in dotted lines the operative position of the corkscrew.

Fig. 5 is a section on line 5—5, Fig. 4.

Fig. 6 is a plan view of the blank from which the body portion of the device is formed.

Fig. 7 is a detail section on the line 7—7, Fig. 2.

As in Letters Patent No. 1,610,158, above referred to, the body of the device or appliance is preferably composed of resilient sheet metal and formed from a blank of substantially the shape shown in Fig. 6. Said body comprises a closure portion or cap 15 having secured thereto, as by means of turned flanges 16, a rubber or other sealing disk 17, said cap 15 having also integral projections forming spring fingers 18 which

are connected with the cap by outwardly disposed spring loops 19, and which are provided with inwardly turned lugs 20 adapted to engage the bead or flange 21 on the bottle neck. One of the spring fingers 18 is extended beyond the neck engaging means 20 to constitute a combined operating lever and crown seal remover 22.

In accordance with the present invention one of the spring loops 19, herein that connecting the cap 15 with the spring finger 18 having the extension 22, is utilized as a hinge knuckle for the attachment of an auxiliary implement, such as a corkscrew 23. To this end said loop 19 is preferably provided with a transverse slot 24 to receive an eye 25 which forms the terminal of the shank 26 of the corkscrew and constitutes a complementary hinge knuckle. The hinge is completed by a pin 27 which passes through the eye 25, engages the interior of the loop 19, and constitutes the hinge pintle. By this construction the corkscrew is effectually connected with the cap by a hinge one knuckle of which is provided by one of the spring loops which, in turn, constitutes an essential portion of the cap retaining means.

Also in accordance with the invention the combined operating lever and crown seal remover 22 is provided with a longitudinally extending outstanding rib 28 the outer end of which is offset and is formed in one side with a socket 29. Said socket is disposed opposite the point of the corkscrew 23 but at one side thereof when the latter is in the position which it normally tends to assume, as shown in Fig. 3, and opens in a direction away therefrom. By springing the corkscrew laterally out of its normal position, as shown in Fig. 2, its point can be engaged with the laterally opening socket 29 as shown in Fig. 7, thereby housing and protecting the point as well as retaining the corkscrew in the normal inoperative position shown in full lines in Figs. 1, 2 and 4. Said point can, however, be readily disengaged from the socket 29 and the corkscrew turned upon its hinge into its operative position shown in broken lines in Fig. 4.

Having thus described my invention, I claim:

1. A compound appliance of the character described comprising a bottle cap having spring fingers provided with means for engaging the bottle neck, one of said fingers having an extension beyond its neck engaging means, and a corkscrew hinged to said cap, said extension having a socket disposed opposite the point of said corkscrew but at one side thereof when the latter is in normal position and opening away therefrom, said corkscrew being adapted to be sprung laterally to engage said point with said socket.
2. A compound appliance of the character described comprising a bottle cap having fingers provided with means for engaging the bottle neck and connected with said cap by outwardly disposed spring loops, one of said loops having a transverse slot, the corresponding fingers having an extension beyond its neck engaging means constituting a combined operating lever, and crown seal remover, a corkscrew having a shank terminating in an eye received in said slot, and a pin passing through said eye and engaging said loop, said extension having a longitudinally extending rib provided in one side with a socket disposed opposite the point of said corkscrew but at one side thereof when the latter is in normal position and opening away therefrom, said corkscrew being adapted to be sprung laterally to engage said point with said socket.

35 In testimony whereof I affix my signature.
ALBERT W. CHARBONNEAU.
